US00D984281S

(12) **United States Design Patent** (10) Patent No.: **US D984,281 S**
Gonzalez et al. (45) Date of Patent: **** Apr. 25, 2023**

(54) CARRIER	3,099,475 A	7/1963	Manizza
(71) Applicant: Graphic Packaging International, LLC , Atlanta, GA (US)	3,118,537 A	1/1964	Copping
	3,128,034 A	4/1964	Weiss
	3,137,109 A	6/1964	Rapata
	3,146,885 A	9/1964	Grantham
	3,156,358 A *	11/1964	Randrup B65D 71/48 206/192
(72) Inventors: Ana Gonzalez , Igualada (ES); Steve M. Gould , Bristol (GB)	3,200,944 A	8/1965	Rapata
	3,223,308 A	12/1965	Weiss
	3,245,711 A	4/1966	Dantoin
	3,257,066 A	6/1966	Williams
	3,281,180 A	10/1966	Spery
	3,302,784 A	2/1967	Copping
	3,387,879 A	6/1968	Wood
	3,404,912 A	10/1968	Watts
	3,410,596 A	11/1968	Slevin, Jr.
	3,432,202 A	3/1969	Ebelhardt
	3,463,535 A *	8/1969	Beart B65D 71/44 294/87.28
(21) Appl. No.: 29/735,178	3,528,697 A	9/1970	Wood
(22) Filed: May 19, 2020	3,587,847 A	6/1971	Graser
(51) LOC (14) Cl. 09-03	3,601,439 A	8/1971	Poupitch
(52) U.S. Cl. USPC D9/752	3,612,266 A *	10/1971	Graser B65D 71/48 206/161
(58) Field of Classification Search	D222,579 S	11/1971	Oglesbee
USPC D9/737, 751-756, 455, 456, 517, 716, D9/719; D7/553.1, 553.4, 553.5, 553.8, D7/555, 701, 708; D3/310-315	3,627,121 A	12/1971	Deasy

(57) CLAIM

The ornamental design for a carrier, as shown and described.

DESCRIPTION

The disclosures of each of U.S. patent application Ser. No. 16/426,050, filed on May 30, 2019, U.S. patent application

Ser. No. 16/426,057, filed on May 30, 2019, U.S. patent application Ser. No. 16/426,060, filed on May 30, 2019, U.S. patent application Ser. No. 16/426,063, filed on May 30, 2019, U.S. patent application Ser. No. 16/426,066, filed on May 30, 2019, U.S. Design Patent application Ser. No. 29/692,992, filed on May 30, 2019, U.S. Design Patent application Ser. No. 29/692,993, filed on May 30, 2019, U.S. Design Patent application Ser. No. 29/692,994, filed on May 30, 2019, U.S. Design Patent application Ser. No. 29/692,996, filed on May 30, 2019, U.S. Design Patent application Ser. No. 29/692,997, filed on May 30, 2019, U.S. patent application Ser. No. 16/598,282, filed on Oct. 10, 2019, U.S. Design Patent application Ser. No. 29/709,918, filed on Oct. 18, 2019, and U.S. patent application Ser. No. 16/829,346, filed on Mar. 25, 2020, are hereby incorporated by reference for all purposes as if presented herein in their entirety.

FIG. 1 is a perspective view of an exemplary embodiment of a carrier showing our new design.

FIG. 2 is a front elevation view of the carrier of FIG. 1, the rear elevation view is a mirror image.

FIG. 3 is a left elevation view of the carrier of FIG. 1, the right elevation view is a mirror image.

FIG. 4 is a top plan view of the carrier of FIG. 1.

FIG. 5 is a bottom plan view of the carrier of FIG. 1; and, FIG. 6 is a plan view of the carrier of FIG. 1 shown in an unfolded configuration.

The broken lines showing cans illustrate environmental structure. All other broken lines represent portions of the carrier. The broken lines form no part of the claimed design.
